UNITED STATES PATENT OFFICE.

RICHARD C. EAST, OF EVANSTON, ILLINOIS.

DESIGN FOR A CRADLE.

58,141.

Specification for Design.

Patented June 14, 1921.

Application filed October 25, 1920. Serial No. 419,543. Term of patent 7 years.

To all whom it may concern:

Be it known that I, RICHARD C. EAST, a subject of the King of England, and resident of Evanston, in the county of Cook and State of Illinois, have invented a new, original, and ornamental Design for a Cradle, (Case 2,) of which the following is a specification, reference being had to the accompanying drawing, forming a part thereof, in which—

Figure 1 is a side elevation, and

Fig. 2 is an end elevation.

I claim:

The ornamental design for a cradle as shown.

In witness whereof, I hereunto subscribe my name this 21st day of October, 1920.

RICHARD C. EAST.

Witnesses:

EDNA V. GUSTAFSON,
ANDREW F. WINTERCORN.
